UNITED STATES PATENT OFFICE

FRANCIA BAUDENON, OF VOREY, FRANCE.

EMBROIDERY IN DIVERS CORDS.

No. 855,274.

Specification of Letters Patent.

Patented May 28, 1907.

Application filed July 18, 1906. Serial No. 326,705.

To all whom it may concern:

Be it known that I, FRANCIA BAUDENON, maiden name Bertholin, a citizen of the Republic of France, residing at Vorey, Haute-
5 Loire, France, manufacturer, have invented certain new and useful Improvements in the Application of Embroidery in Divers Cords, of which the following is a specification.

My invention relates to an improved mode
10 of support for the applications of embroider-
ies in divers cords, as, for example, raised
applications, known in France as "plumetis-
express." The said applications are generally
15 secured on the sheet of paper which
keeps them well in the required shape up to
the time when they are used and even when
they are being put on the fabric. The said
sheet not only constitutes a good support for
20 shape, but it has also the advantage of pre-
senting surfaces which are suitable for receiv-
ing printed indications as to the mode of use
and the like. Yet it has the inconveniency
25 of being difficult to tear away in the inner
portions of the design, so that there is the
risk of damaging either the application or the
fabric. In order to avoid this inconvenience
several kinds of either open or narrow sup-
30 ports have been devised, but as they must
always be very thin and flexible, none of
them are sufficiently solid to keep the appli-
cation in the same shape.

My invention has for its object to still use
these paper supports on account of the ad-
35 vantages they offer, while avoiding at the
same time the difficulty of tearing the sup-
port away after the application has been put
on the fabric. For that purpose, the appli-
cation is pasted onto a sheet of paper and the
40 said sheet is perforated, or partially, or
wholly, cut away on a line along the inner
contours of the design. By this means, the
application is firmly held in the required
shape, for it is connected by the whole of its
45 outer contour to a sheet of paper of sufficient
area to be enabled to keep its shape; further-
more, the difficulty of tearing the paper away
along the inner contours is done away with
by reason of the previously cut or perforated
50 line. The tearing of the paper away along

the outer contours may again be facilitated
by means of perforations previously made.

The accompanying drawing shows a plu-
rality of embodiments of my invention.

Figure 1 represents an application on its 55
support and then shows the said support sep-
arately; and Fig. 2 and 3 represent in the
same manner modified forms or embodi-
ments.

In Fig. 1, the sheet of paper *a*, is cut away 60
by continuous cuts *b*, along the inner con-
tours of the application *c*. Portions are
therefore cut away in the support before the
latter is placed on the fabric, and all that
need be done is to tear the paper away along 65
the outer contours of the application after
the latter has been put on the fabric, which is
not very difficult to do. For certain forms
of letters or designs, small bands *d* may be
left at the inside of the design to sustain such 70
portions of the application as may require sus-
tenance.

In Fig. 2, the sheet of paper *a* is also cut
away by continuous cuts *b* along the inner
contours of the application, and it is further 75
cut away by perforated lines *e* along the
outer contours, in order to still more facili-
tate the tearing of the paper away after the
embroidery has been put onto the fabric.

In Fig. 3, the sheet of paper *a* is cut away 80
on perforated lines *b* along the inside of the
application, and on other perforated lines *e'*
at the outside. The latter perforated lines
are optional.

In these divers forms or embodiments, the 85
supporting sheet of paper is, in spite of the
cut away portions and especially when the
latter are made on perforated lines, always
enabled to retain its shape sufficiently to keep
90 the applications in their proper form.

It will be understood that the application
may consist of any kind of design, letter,
monogram, or the like, and may be made of
any sort of cord.

Claims—

1. The combination of a cord embroidery application with a supporting sheet of paper, the said sheet of paper being cut away along the inner contours of the application.
2. The combination of cord embroidery 100

application with a supporting sheet of paper; the said sheet being cut away by a continuous cut along the inner contours of the application and on a perforated line along the outer contours of the said application.

3. The combination of a cord embroidery application with a supporting sheet of paper, that part of the sheet covered by the application being partially separated from the re-

mainder on lines following the contour of the application.

In testimony, that I claim the foregoing as my invention, I have signed my name in presence of two subscribing witnesses.

FRANCIA BAUDENON.
